UNITED STATES PATENT OFFICE.

MANUEL E. JASPER, OF WIARTON, CANADA, ASSIGNOR TO DAVID M. JERMYN, OF WIARTON, ONTARIO, CANADA.

TRUSS.

SPECIFICATION forming part of Letters Patent No. 724,014, dated March 31, 1903.

Application filed September 18, 1902, Serial No. 123,952. (No model.)

To all whom it may concern:

Be it known that I, MANUEL EDWARD JASPER, of the town of Wiarton, in the county of Bruce, Province of Ontario, Canada, have invented certain new and useful Improvements in Trusses, of which the following is a specification.

The object of the invention is to devise a comfortable truss which will effectually hold any rupture, while giving the wearer the utmost freedom of motion; and it consists, essentially, in the construction hereinafter described, and illustrated in the accompanying drawings, in which—

15 Figure 1 is a perspective front view of the truss as arranged for a double rupture, and Fig. 2 a perspective detail of the back pad. Fig. 3 is a detail showing the peculiar curvature of the pad-holder J.

20 In the drawings like letters of reference indicate corresponding parts in the different figures.

A is a divided metal band adapted to fit around the waist of the wearer, and B a back plate to which the rear ends of the halves of the band A are adjustably yet rigidly connected, as hereinafter described. If the truss is to be used on a single rupture, the front end of one half of the metal waistband is bent 25 back upon itself toward the side of the body and is then curved downward, rearward, and inward to follow the groin until the point is reached at which the rupture exists. To the end of the pad-holder J so formed is then ad- 30 justably secured a truss-pad C, as hereinafter described. If a double rupture exists, the front end of the other half of the metal waistband is similarly continued to form a pad-holder and provided with a suitable truss-pad.

35 40 Where the front ends of the waistband are bent back upon themselves I provide the plates D, each provided with a socket E, adapted to receive the loop of the band, the latter being secured therein by means of the set-screw F. To the backs of the plates B and D may be connected suitable pads of felt or other material to make the apparatus comfortable to the wearer. The wires may also be covered in any suitable manner.

45 50 The plates E have connected thereto the strap and buckle G, forming a flexible and ad-

justable connection between the front ends of the waistband, by means of which the truss may be suitably adjusted around the waist.

When in use, the metal waistband is quite 55 loose on the body and the trouble and inconvenience caused by the ordinary tight-fitting adjustments are entirely obviated. At the same time it is sufficiently rigid to afford a suitable attachment for the truss-pads. These latter being connected to the downwardly-extending spring ends of the waistband are given a light yet firm pressure inward and upward against the rupture, securely holding it under all circumstances. It is not, of course, 60 essential that these spring ends be formed integral with the waistband, as they might readily be made out of separate pieces of material; yet I find my present arrangement a convenient method of manufacture. 65

70 The adjustable connection of parts of the metal waistband to the back plate B is formed by the bridges H fitting over the ends of the waistband and held down by the screws c against the raised plate a, secured to the back 75 of the plate B. By loosening the screws the waistband can be adjusted any time and afterward securely clamped. The bridges and plate are preferably slightly recessed to receive the band. The ends of the front portions of the waistband pass through lugs I, formed on the back plate of the truss-pads, and are held therein by means of the set-screws d. It is thus easy to adjust the truss-pads in any desired position, longitudinally 80 and rotatably. 85

It is an important feature of my truss that the metal band circling the body is formed as a waistband and does not run directly down to the truss, as is usually the case. My construction adds much to the comfort of the wearer, as the disagreeable downward pressure of such faulty trusses is entirely obviated. 90

When manufacturing the truss, many variations might be made from the exact construction herein described which would yet fall within the scope of the invention. 95

What I claim as my invention is—

1. In a truss a spring-metal waistband 100 adapted to press on the body at the back and front, in combination with a spring-metal pad-

holder rigidly secured to the front of the waistband, curved out toward the side of the body, and then curved downward, inward and rearward to follow the groin and exercise a 5 spring-pressure against the body; and a truss-pad secured to the end of the pad-holder, substantially as described.

2. In a truss a divided spring-metal waistband, having a rigid adjustable connection 10 between the rear ends of its parts and a flexible adjustable connection between the front ends of its parts, in combination with a spring-metal pad-holder rigidly secured to the front of the waistband, curved out toward the side 15 of the body, and then curved downward, inward, and rearward to follow the groin and exercise a spring-pressure against the body; and a truss-pad secured to the end of the pad-holder, substantially as described.

20 3. In a truss a spring-metal waistband divided in front and having a flexible adjustable connection between the ends, in combination with a spring-metal pad-holder rigidly secured to the front of the waistband, 25 curved out toward the side of the body and then curved downward, inward and rearward 10 to follow the groin and exercise a spring-pressure against the body; and a truss-pad secured to the end of the pad-holder, substantially as 30 described.

4. In a truss a spring-metal waistband divided in front and having a flexible adjustable connection between the ends in combination with a spring-metal pad-holder formed 35 by bending the end of the waistband back toward the side of the body and then curved downward, inward and rearward to follow the 40 groin and exercise a spring-pressure against the body; and a truss-pad secured to the end of the pad-holder, substantially as described.

5. In a truss a divided spring-metal waistband having a rigid adjustable connection between the rear ends of its parts and a flexible adjustable connection between the front 45 ends of its parts, in combination with a spring-metal pad-holder formed by bending the end of the waistband back toward the side of the body and then curved downward, inward and rearward to follow the groin and exercise a 50 spring-pressure against the body; and a truss-pad secured to the end of the pad-holder, substantially as described.

6. In a truss a spring-metal waistband adapted to press on the body at the back and 55 front, in combination with a spring-metal pad-holder rigidly secured to the front of the waistband, curved out toward the side of the body, and then curved downward, inward and rearward to follow the groin and exercise 60 a spring-pressure against the body; and a truss-pad longitudinally and rotatably adjustable on the end of the pad-holder, substantially as described.

7. In a truss a spring-metal waistband divided in front and having a flexible adjustable connection between the ends, in combination with a spring-metal pad-holder rigidly secured to the front of the waistband, curved out toward the side of the body and 70 then curved downward, inward and rearward to follow the groin and exercise a spring-pressure against the body; and a truss-pad longitudinally and rotatably adjustable on the end of the pad-holder, substantially as 75 described.

Toronto, September 4, 1902.

MANUEL E. JASPER.
